UNITED STATES PATENT OFFICE.

WILLIAM A. C. OAKS, OF ANTRIM, NEW HAMPSHIRE, ASSIGNOR TO GOODELL COMPANY, OF SAME PLACE.

GUARD FOR CARVING-FORKS.

SPECIFICATION forming part of Letters Patent No. 277,052, dated May 8, 1883.

Application filed March 7, 1883. (No model.)

To all whom it may concern:

Be it known that I, WILLIAM A. C. OAKS, a citizen of the United States, residing at Antrim, in the county of Hillsborough and State of New Hampshire, have invented certain new and useful Improvements in Table-Cutlery, of which the following is a specification.

My invention consists of an improved spring-guard for carving-forks, so made and applied to the fork as to serve both as a guard and as a support for the fork when in use, as herein-after more fully described and claimed.

Figure 1 is a perspective view of a carving-fork with my improved guard attached. Fig. 2 is a plan view of the fork prepared to have my guard attached. Fig. 3 is a view of the guard in front elevation. Fig. 4 is a side view of the guard, showing the depressions or corrugations for pin and the form of the lip or tongue.

Similar letters refer to similar parts throughout the views.

H is the shank of the fork.

A is a rectangular slot made in the shank of the fork. The end marked *a* is sloping. The other sides of the slot are perpendicular to the faces of the shank.

B is a hole drilled through the shank parallel to the face of the shank, passing about midway through the slot A.

C' C' is the improved guard. This guard consists of four parts in one piece—C, the top, slightly bent from the plane of the rest of the guard; C' C', the legs which form a support for the fork when not in use, and E the tongue, bent slightly out of the plane of the rest of the guard and then bent abruptly at right angles, with a slight curve at the point of flexure.

D is the pin or pivot passing between the legs C' C' and the tongue E, and through the hole B in the shank of the fork. This pin is retained in position by certain depressions in the legs C' C' and the tongue E. Upon this pin the guard turns.

Having made a carving-fork in the usual manner, I then punch or otherwise make a

slot in the shank of the fork, as shown at A in Fig. 2, the end of the slot nearest the prongs of the fork being made sloping on its upper surface, to allow of the guard being turned down, and yet prevented from going too far. The slot cannot be cut through square all the way, because it is necessary to leave a bearing underneath as a stop for the tongue of the guard. At the point indicated at B, Fig. 2, by dotted lines I drill a hole passing midway through the slot A and parallel to the face of the shank. This hole is intended for the reception of a pin, D, to hold the guard, as shown in Fig. 1. The guard consists of a piece of steel, of the form shown in Figs. 3 and 4, punched out of sheet metal and bent as shown in Fig. 4.

C' C' are small depressions or corrugations made transversely to the legs C' C', to form a recess for the retention of the pin D.

The tongue E is bent at the point E, at first slightly outward and then at right angles to itself to form the part f, which acts as a stop when the guard is raised for use. The legs C' C' and tongue E receive a spring temper, so as to press firmly against the pin D and allow the whole guard to turn upon this pin as a pivot, the friction being sufficient to retain the guard in any desired position. That portion of the tongue E bent as at f touches by its upper surface and end, when raised to its proper position, the under side of the shank H at that point of the slot *a* which is not entirely cut through, and prevents the knife from glancing off and endangering the hand, as would be the case if the guard were free to move toward the handle of the fork without hindrance.

The shape of the various parts, being to some extent a matter of fancy, may be slightly varied without interfering with the usefulness of the invention.

Having now fully described my invention above set forth, what I claim, and desire to secure by Letters Patent, is—

1. The legs C' C' and lip or tongue E, corrugated at the points C' C' and E, and bent

in such a manner as to form springs pressing against the pin D to hold the guard in any desired position.

2. The lip or tongue E, forming a center prong of the guard, bent at or nearly at right angles, in combination with the shank of the fork, against which it abuts on the under side at the point *a* by its outer end, *f*, and acts as

a stop to prevent the guard being pressed too far back.

In witness whereof I have hereunto set my hand.

WILLIAM A. C. OAKS.
